CLAIM

I claim the ornamental design for a poultry cooking apparatus, as shown and described.

DESCRIPTION

FIG. 1 is a perspective view of a poultry cooking apparatus in accordance with the present invention;

FIG. 2 is a side view of a poultry cooking apparatus in accordance with the present invention;

FIG. 3 is a top view of a poultry cooking apparatus in accordance with the present invention; and,

FIG. 4 is a bottom side view of a poultry cooking apparatus in accordance with the present invention.

The broken lines shown in the drawings are for illustrative purposes only and form no part of the claimed design.
